UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed December 11, 1918, Serial No. 286,312. Renewed May 28, 1925.

This invention relates to mining machines, and especially to coal mining machines of the type comprising a flat cutter bar provided with a continuously running cutter chain, 5 although not necessarily limited to machines of this particular type.

The invention has for its general object to provide an improved machine of practical design adapted to cut a kerf in a mine face in substantially any desired plane within the range of operation of the machine, said 10 machine comprising improved mechanism whereby the same may be conveniently adjusted, operated, and propelled from place to place about the mine.

More specifically, the invention contemplates certain improvements in machines of the character disclosed and claimed in my prior application for Letters Patent, filed 20 Nov. 1, 1918, Serial No. 260,708, whereby the range of adjustability of the machine is increased, and whereby its control, adjustment, and operation are facilitated.

The foregoing and other objects of the invention, together with means whereby the same may be carried into effect, will best be understood from the following description of one form or embodiment thereof shown for purposes of illustration in the accompanying drawings.

In said drawings,—

Fig. 1 is a side elevation, and Fig. 2 a plan view, of the complete machine, the outer end of the cutter bar being broken away.

Fig. 3 is an enlarged longitudinal section, taken substantially on the line 3—3, Fig. 2, of the adjustable cutter bar head.

Fig. 4 is a vertical section taken substantially on the line 4—4, of Figs. 3 and 5.

Fig. 5 is a horizontal section on the line 5—5, Fig. 3.

Fig. 6 is a vertical section taken substantially on the line 6—6, Fig. 1, with the cutter head slide in a different position.

Fig. 7 is a horizontal section of the selective transmission mechanism for controlling the propulsion of the machine truck and the angular adjustment of the motor casing and parts carried thereby.

Fig. 8 is a vertical section taken substantially on the line 8—8, Fig. 7.

Fig. 9 is a transverse vertical section on the line 9—9, Fig. 2, certain of the gearing being omitted to facilitate illustration.

Fig. 10 is a section on the line 10—10, Fig. 9.

Figs. 11 and 11^a are vertical sections taken substantially on the lines 11—11 and 11^a—11^a, respectively, Fig. 7.

Fig. 12 is a diagrammatic plan view illustrating the operation of the machine in cutting a horizontal kerf in a mine face in the operation of driving an entry.

Fig. 13 is a diagrammatic view, in side elevation, illustrating the operation of the machine in top cutting.

Fig. 14 is a diagrammatic plan view illustrating the operation of the machine in shearing or inserting a vertical kerf in a mine face.

Fig. 15 is a diagrammatic view illustrating some of the possible adjustments of the cutter bar.

Fig. 16 is a diagrammatic view, in side elevation, illustrating the operation of the machine in undercutting at an inclination.

Fig. 17 is a diagrammatic plan view illustrating the use of the machine as a mounted longwall machine.

Fig. 18 is a diagrammatic view, in end elevation, illustrating the machine operating as a mounted longwall machine in cutting an inclined kerf in a face at one side of the trackway.

Referring first to Figs. 1 and 2, the apparatus as a whole comprises a truck consisting of a truck body 20 mounted on wheels 21 secured to front and rear axles 23 and 24, respectively, and adapted to run upon a suitable trackway 22. Upon said truck is mounted the mining mechanism including a motor casing 25 and a forwardly extending cutter bar 26 provided with the usual cutter chain 27, said cutter bar being supported on said truck by means hereinafter more fully described.

In order to permit adjustment of the cutter bar 26 with respect to the trackway 22 about a transverse horizontal axis, the rear axle 24 as herein shown is journaled in boxes 100

28 (see Figs. 9 and 10) mounted in guideways 29 in depending brackets 30 carried by the truck body 20, whereby said axle and truck body are relatively vertically movable, 5 said truck body during such vertical movement turning about the axis of the front axle 23. For the purpose of relatively adjusting the truck body 20 and axle 24 and of retaining the parts in adjusted position, said axle, 10 as herein shown, is provided with a collar 31 to which is secured, as by a pin 32, a rod 33 having a threaded upper end cooperating with a threaded sleeve 34 provided with a hand wheel 35. The sleeve 34 is rotatably 15 mounted in a hanger or bracket 36 projecting downwardly from a casing 37 bolted to the truck body 20 and enclosing certain transmission mechanism hereinafter described.

Within the casing 25 is the usual electric 20 or other motor 19, governed by a suitable controller 38 (Fig. 2), preferably secured to the casing 37, said motor being supplied with current through a cable wound upon a reel 39 journaled in the truck body 20, said 25 reel being electrically connected with the motor by the usual conductors (not shown) and, as is usual in machines of this character, being rotated, by means hereinafter referred to, to wind up or pay out the cable as the 30 truck is propelled in one direction or the other along the track 22.

The motor casing 25 is mounted in the truck body 20 for angular adjustment about a substantially horizontal longitudinal axis, 35 and to this end the cylindrical forward end thereof is rotatably supported in an annular frame member 40 (see particularly Fig. 6) at the forward end of said truck body, while the rear end of said casing is reduced in 40 diameter and is formed with a cylindrical projection 41 (see Fig. 9), which is journaled in a sleeve 42 (see also Fig. 2) forming a part of a transverse truck body frame member 43.

The motor shaft 44 (Fig. 9) is journaled 45 at its rear end in the bracket or hanger 36 and is provided with a worm 440 (Fig. 2) meshing with a worm gear 45 on a transverse shaft 46 (see Figs. 7 and 8) journaled in the casing 37. Said shaft 46 has keyed thereto 50 within said casing a pinion 47 and a worm 48, the latter having a hub 490 journaled in a suitable bearing in the casing 37. The worm 48 meshes with a worm gear 49 loosely mounted on a driving shaft 50, said worm

55 gear being adapted to be clutched to said shaft by means hereinafter described, whereby said shaft may be rotated at a relatively high speed from the shaft 46. The shaft 50 is journaled adjacent one end in a bearing 60 51 formed on one end of the casing 37, and at its opposite end is rotatably mounted in a sleeve 52, the latter having a head 53 which is rotatably mounted in a sleeve-like extension 54 formed on the end of the casing 37 65 opposite the bearing 51.

Fast upon one end of the shaft 50 is a bevel gear 55 which meshes with a bevel gear 56 (Fig. 2) on a transverse shaft 57 journaled in the truck body 20. Secured to one end of the shaft 57 is a sprocket 58 (see also Fig. 1) 70 connected by a chain 59 with a sprocket 60 on the forward axle 23, whereby, by properly controlling the rotation of the shaft 50, the truck may be propelled along the track 22 in either direction. Fast upon the opposite end of the shaft 57 is a sprocket 61, connected by a chain 62 with a sprocket 63 on the shaft of the cable reel 39, whereby said reel may be rotated as above explained to wind up or 75 pay out the cable.

The pinion 47 meshes at opposite sides with gears 64 and 65 (Fig. 7) loosely mounted on stud shafts 66 and 67 suitably supported in the casing 37, said gears having extended sleeve-like hubs formed with worms 68 and 69 (see 80 Figs. 11 and 11^a) which mesh, respectively, with worm gears 70 and 71 loosely mounted on the shaft 50 but adapted to be clutched thereto, as hereinafter more fully described. The worms 68 and 69 are of opposite pitch, 85

whereby the worm gears 70 and 71 are rotated in opposite directions, and are preferably of less steep pitch than the worm 48, while the gears 64 and 65 are larger than the pinion 47, so that said gears 70 and 71 90 are rotated at a relatively slow speed with respect to the speed of rotation of the gear 49. The gear 49, when clutched to the shaft 50, is employed for propelling the truck from place to place about the mine at a relatively high 95 speed (the motor 19 being reversed by suitable operation of the controller 38 when it is desired to change the direction of travel of the truck), while the gears 70 and 71, when clutched to said shaft, are employed for moving the truck at a relatively slow speed in 100 one direction or the other during the cutting operation. The sleeve 52 has formed at its forward end a pinion 73 which meshes with a gear 74 (see Fig. 2) formed on the journal 105 41 (Fig. 9) of the motor casing 25, whereby the sleeve 52, when clutched to the shaft 50, may be employed, through the pinion 73 and gear 74, for the purpose of rotating and angularly adjusting said motor casing in its bearings.

For selectively connecting the gears 49, 70, and 71, and the head 53 of the sleeve 52 to the shaft 50, the following mechanism is provided. Keyed to the shaft 50 between the gears 49 and 70 (Fig. 7), is a hub 75, while keyed to said shaft between the gear 71 and the head 53 is a second similar hub 76. Interposed between the hub 75 and the gears 49 and 70 are multiple disk clutches 77 and 78, respectively, while interposed between the hub 76 and the gear 71 and head 53 are similar clutches 79 and 80. The clutches 77 and 78 may be alternatively set to connect the gear 49 or the gear 70 with the hub 75 by means of 110 115 120 125 130

a clutch controlling ring 81 operated by a clutch shifter 82, controlled by a suitable lever or handle 83 (Fig. 2) at the exterior of the casing 37. Similarly, the clutches 79 and 80 may be operated, through a clutch controlling ring 84, by a clutch shifter 85 connected with a lever or handle 86 similar to the lever 83. By operating the lever 83 to move the clutch controlling ring 81 in one direction or the other from a neutral position in which the clutches 77 and 78 are both released, the shaft 50 may be driven by either the gear 49 or the gear 70. By similarly operating the lever 86 to move the clutch controlling ring 84, said shaft 50 may be driven through the gear 71, or the sleeve 52 may be clutched to said shaft for rotation therewith when said shaft is driven by either the gear 49 or the gear 70.

The head 53 is formed with a series of peripheral openings or recesses 87 (Fig. 7) adapted to receive a locking pin 88 (Fig. 2) which may be inserted through a suitably disposed opening in the casing extension 54 to lock the head 53, and consequently the sleeve 52, against rotation when not employed for the purpose of turning the motor casing 25. When said head and sleeve are thus locked against rotation, operation of the lever 86 to set the clutch 80, and thereby connect the shaft 50 with said sleeve, will serve to hold said shaft, and consequently the truck, stationary, thereby affording braking means for said truck.

As will be readily understood, angular adjustment of the motor casing 25, by which the cutter bar 26 is carried, will serve to position said cutter bar to cut kerfs in different planes. For adjustably supporting said cutter bar upon said casing in such a manner as to provide for further adjustment of said cutter bar and to permit the same to assume a wide variety of positions, the following means are provided.

Referring to Figs. 1, 2, 3, 5, and 6, the forward end of the motor casing 25 has secured thereto, as by bolts 90, a cylindrical head or casing 91 formed with a pair of parallel, oppositely flanged ways 89 constituting a guide of which the longitudinal axis extends substantially diametrically thereacross. Mounted for rectilinear movement on the ways 89 is a slide or carriage 92 having a hub 93 on which is rotatably mounted a turret 94, the axis of said hub, and consequently the axis of rotation of the turret 94, being parallel to the axis of the motor shaft 44. The turret 94 is in turn provided with a hub 95 having its axis transverse to the axis of the hub 93 but in the same plane therewith, on which hub 95 is rotatably mounted a second turret 96 carrying the cutter bar 26.

For actuating the cutter chain 27, and for controlling the movements of the turrets 94 and 96 about their axes, and the movement of and slide 92 on the ways 89, the following

mechanism is provided, reference being had particularly to Figs. 3 to 6.

Journalized in the hub 93 is a shaft 102 to which is keyed, within the casing 91, a gear 101 operatively connected by an intermediate gear 98 with a pinion 97 fast upon the forward end of the motor shaft 44. The intermediate gear 98 is rotatably mounted on a stud 99 projecting from an annulus 100 slidably or rotatably mounted in an annular guideway formed in the front head of the motor casing 25 and concentric with the axis of the shaft 44, said annulus being retained in said guideway by an inner disk 103 and an outer annular gib 104 suitably secured to said head. The stud 99 is connected with the shaft 102 by a link 105 loosely engaging at its ends said stud and shaft, respectively, whereby, as the slide 92 is moved on the ways 89, said link will hold the gears 98 and 101 in spaced relation and therefore in interengagement, while movement of the annulus 100 in its guideway will retain the stud 99 at a fixed distance from the axis of the shaft 44, and thereby hold the gear 98 in operative engagement with the pinion 97, so that the driving connection between the pinion 97 and gear 101 is maintained irrespective of the position of adjustment of the slide 92. Carried by the forward end of the shaft 102 is a bevel pinion 106 (Fig. 3) meshing with a bevel gear 107 having a hub 108 journalized in the hub 95 coaxially therewith. Also rotatably mounted in the hub 95 and connected with the hub 108 for rotation therewith, is the hub 109 of a sprocket wheel 110 for driving the cutter chain 27. The hubs 108 and 109 are keyed to a sleeve 111 within which is rotatably mounted a shaft 112 arranged coaxially with the hub 95 and having fast upon its end a pinion 113 meshing with an idler gear 114 journalized upon a disk 115 secured, as by bolts 116, to the turret 96, said gear 114 meshing with a gear 117 fast upon a shaft 118 disposed substantially parallel to the shaft 112 and journalized in a suitable bearing in the turret 96. Fast upon the shaft 118 is a pinion 119 cooperating with a segmental rack 120 carried by the turret 94.

As will now be seen, rotation of the motor shaft 44 will be transmitted through the pinion 97, gears 98 and 101, shaft 102, and gears 106 and 107, to the sleeve 111 and also to the cutter chain sprocket 110 to actuate the cutter chain. It will also be seen that, by suitably connecting the sleeve 111 with the shaft 112, so as to cause rotation of said shaft, motion will be transmitted through the pinion 113, gears 114 and 117, and shaft 118 to the pinion 119, causing the latter, by cooperation with the rack 120, to swing the turret 96 and cutter bar 26 about the axis of the hub 95.

For so connecting the sleeve 111 and shaft 112 as to cause rotation of said shaft in either direction and at different speeds, a friction

ally controlled reduction and reversing gearing is employed. The sleeve 111 is formed at one end with an eccentric portion 121 upon which is rotatably mounted, as by a roller or other antifriction bearing 122, an annulus 123 having formed thereon two spur gears 124 and 125. The gear 125 cooperates with a larger internal gear 126 having a hub keyed or otherwise secured to the shaft 112; while 10 the gear 124 cooperates with a second internal gear 127 formed on a sleeve 128 journaled in suitably formed bearings in the turret 94 and in a bracket 129 carried thereby. The ratio of the number of teeth on the gear 125 to the 15 number of teeth on the gear 126 is different from the ratio of the number of teeth on the gear 124 to the number of teeth on the gear 127, so that the whole constitutes a compound epicyclic internal gear train of familiar form. 20 Rotation of the eccentric 121 causes the gears 124 and 125 to travel about the interior of the gears 127 and 126, respectively, whereby, if the gear 127 be held stationary, the unequal ratios of the numbers of teeth on the gears 25 of the several couples will cause the gear 126, and consequently the shaft 112, to be rotated at a greatly reduced speed with respect to the speed of rotation of the sleeve 111, and (if the parts be properly proportioned) in the 30 opposite direction; and whereby, if the gears 126 and 127 be clutched together for rotation in unison, the unequal teeth ratios referred to will cause the gears to jam, so that the entire train, including the gears 124, 125, 126, 35 and 127, together with the shaft 112, will be caused to rotate in unison with the sleeve 111. Means are accordingly provided whereby the gear 127 may be held stationary or may be clutched to the gear 126, said means being 40 of such a nature as to permit slipping of the parts under stresses in excess of a predetermined maximum in order to prevent injury to the machine under conditions of overload, and, as herein shown, comprising a reversible 45 friction device constructed and arranged as follows. The turret 94 is provided with an opening disposed in alinement with the shaft 112 and closed by a cap 130 bolted or otherwise secured to said turret, and with an inwardly extending annular flange 131 surrounding said opening, while the gear 126 is formed with a similar annular flange 132 disposed substantially in alinement with the flange 131. The sleeve 128 is adapted to be 50 clutched to either the flange 131 or the flange 132 by means of friction disk clutches 133 and 134, respectively, which may be rendered selectively operative by means of a clutch controller comprising a ring 135 interposed 55 between said clutches and connected by trunnions 136 with an annulus 137 rotatably mounted in an annular groove in a sleeve 138, said sleeve 138 being, for convenience in assembly, formed in two parts in threaded engagement with one another. As the parts are

shown in Fig. 3, downward movement of the sleeve 138 and clutch controller 135 will render operative the clutch 134 to connect the gears 126 and 127, while upward movement of said sleeve and controller will disengage the clutch 134 and render operative the clutch 133 to connect the sleeve 128 with the flange 131, thereby holding the gear 127 stationary.

For operating the clutch controlling sleeve 138, there is provided a second sleeve or operating member 139 slidably mounted for longitudinal movement on an annular flange 140 projecting inwardly from the cap 130, said sleeve being held against rotation with respect to said cap by means of a pin 141 carried by said flange and engaging an internal longitudinal groove in said sleeve. For moving the sleeve 139 longitudinally, there is provided a screw 142 journaled in the cap 130 and in threaded engagement with said sleeve or member 139, said screw being provided at its outer end beyond the cap 130 with a hand wheel 143. The outer end of the sleeve 138 is formed with an interior shoulder 144 which, when the parts are in neutral or normal position with both clutches 133 and 134 disengaged, registers with a nut 145 on the exteriorly threaded outer end of the sleeve or member 139. The sleeves 138 and 139 are provided, respectively, with internal and external shoulders 146 and 147, which, when the parts are in the normal or neutral position referred to, also register with one another. Engaging the shoulder 144 and nut 145, is a washer 148, while engaging the shoulders 146 and 147 is a similar washer 149, and between these washers 148 and 149 is interposed a spring 150 located in a recess between the sleeves 138 and 139.

As will now be seen by referring to the parts as shown in Fig. 3, downward movement of the sleeve 139, by operation of the hand wheel 143 and screw 142, will be transmitted, through the nut 145, washer 148, spring 150, washer 149, and shoulder 146, to the sleeve 138, causing downward movement of said sleeve and of the clutch controlling ring 136, and thereby rendering operative the clutch 134 to connect the gears 126 and 127. Similarly, upward movement of the sleeve 139 will be transmitted through the shoulder 147, washer 149, spring 150, washer 148, and shoulder 144, to the sleeve 138, causing upward movement of said sleeve and engagement of the clutch 133 to connect the sleeve 138 to the flange 131 so as to hold said gear 127 stationary. It will be seen that movement of the sleeve 139 in either direction is transmitted to the sleeve 138 through the spring 150, so that the power transmitted through the clutches 133 and 134 is limited by the resistance of said spring to yielding under compression, which resistance may be determined by subjecting said spring to a suitable initial compression.

As will now be seen, by a proper adjustment of the hand wheel 143, rotation of the sleeve 111 may be transmitted through the shaft 112 and intermediate connections to the pinion 119, which, by engagement with the rack 120, will cause the turret 96 and cutter bar 26 to be swung about the axis of the shaft 112 and hub 95, said swinging of the turret and cutter bar comprising a relatively slow movement in one direction, or a relatively rapid movement in the opposite direction. As above explained, the cutter chain 27 is continuously actuated by the sprocket 110, and the setting of the bits in said chain is such with respect to the operation of the cutter bar that the relatively slow swinging movement of said bar constitutes the operative or cutting movement thereof, while the relatively rapid swinging movement of said bar in the opposite direction constitutes the idle or positioning movement of said bar.

Provision is made whereby the turrets 94 and 96 may be locked against angular movement about their several axes of rotation, whereby the slide 92 may also be locked against rectilinear movement on the ways 89, and whereby the mechanism above described for swinging the turret 96 and cutter bar 26 may also be employed for turning the turret 94 about its axis or for moving the slide 92 on its ways for the purpose of positioning said turret and slide in accordance with the requirements. To this end, the turret 96 is formed with a hooked flange or lip 151 (see Figs. 1, 2, and 3) which extends over a segmental portion 152 of the turret 94 adjacent the segmental rack 120. Said segmental portion 152 is formed with a series of openings 153 to receive a locking pin 154 passed through an opening in the lip 151, whereby the turret 96 may be locked against angular movement to the turret 94 in any desired angular position. The pin 154 is preferably formed with a head 155 having a projection 156 adapted in any position of the turret 96 to engage a segmental lip or flange 157 on the turret 94, whereby said pin may be retained in locking position against accidental dislodgment, said projection being, however, disengageable from the lip 157, to permit the pin to be removed, by giving said pin a quarter turn. Similarly, the turret 94 is formed adjacent the slide 92 with an annular flange 158 provided with one or more apertures 159 to receive one or more pins or bolts 160 which may also selectively engage threaded openings 200 (Fig. 6) of a circular series formed in said slide, whereby said turret can be locked against angular movement to said slide in any desired adjusted angular position. Also for locking the slide 92 against movement on its ways, the flanges of said ways are formed with notches 161 (see Fig. 6) to receive locking pins 162 (see also Fig.

5) which may be inserted in suitably disposed openings 163 in said slide.

In order to turn the turret 94 about the axis of the hub 93, the pins 154 and 162 are placed in locking position, the bolt or bolts 160 removed, and the hand wheel 143 operated to throw in the clutch 133, thereby rendering operative the transmission connections between the sleeve 111 and the pinion 119. Inasmuch as the pin 154 locks the turret 96 against movement by the cooperative action of the pinion 119 and rack 120, the sleeve 111 will react through the gear 107 upon the gear 106, causing the former gear to travel about the axis of the latter and consequently rotate the turret 94 upon its axis. It will be seen that any desired speed of rotation may be obtained by suitable adjustment of the friction device to permit more or less slipping of the parts. When the desired angular position of said turret is reached, the bolts 160 may be slipped into locking position through the openings 159 and into engagement with the proper openings 200 to lock said turret in said position.

For the purpose of adjusting the position of the slide 92 upon its ways, the locking pin 154 and bolts 160 are placed in operative position and the pins 162 removed. The transmission gearing from the pinion 97 to the pinion 119 being thus locked against operation, rotation of said pinion 97 will cause the gear 98 to travel bodily therearound, so that said gear, together with the link 105, will operate as a toggle mechanism to move the slide 92 on its ways into any desired position, in which it may be locked by reinsertion of the locking pins 162. In order to facilitate this adjustment of the slide 92 upon its ways, the turret 94 may, and preferably will, be previously turned upon its axis to bring said ways into a substantially horizontal position.

From the foregoing, it will be seen that the motor casing 25, carrying with it the entire mechanism or cutter head shown in Fig. 3, may be turned to any desired angular position about the horizontal axis of said motor casing, that in any angular position of said motor casing the slide 92 may be moved transversely thereof on the ways 89, carrying with it the turrets 94 and 96, that in any position of said slide the turret 94 may be turned to any angular position about the axis of the hub 93, and that in any angular position of the main cutter head or the turret 94, or in any position of the slide 92 on the ways 89, the turret 96, carrying with it the cutter bar 26, can be swung about the axis of the hub 95. These permissible adjustments render the cutter bar 26 capable of assuming a wide variety of positions in order to swing and to cut a kerf in substantially any desired plane within the range of operation of the machine. Some of these positions are diagrammatically illustrated

in Fig. 15, wherein A denotes the axis of rotation of the motor casing 25, wherein the lines B¹ and B² represent two positions, 90° apart, of the path of movement of the slide 92 as the cutter head is rotated about the axis A, and wherein the letters C and c with various exponents indicate positions of the axis of rotation of the turret 94 in various positions of adjustment of the main cutter head and of the slide 92. Obviously, the ways 89 may be made of any length to provide for any desired range of movement of the slide 92. For convenience of illustration in Fig. 15, however, C^{1a} and C^{1b} may be taken 10 to represent the extreme outer and inner positions, respectively, of the axis of rotation of the turret 94 when the motor casing 25 is turned into the position to bring the shaft 102 vertically above the shaft 44, as shown 15 in Figs. 1, 3, 4, and 6, while c^{1a} and c^{1b} may similarly be taken to indicate the extreme inner and outer positions of said axis when the main head has been turned through 20 an angle of 180° to bring the shaft 102 vertically beneath the shaft 44. Similarly, the 25 letters C^{2a}, C^{2b}, c^{2a}, and c^{2b} may be taken to represent opposite extreme positions of the axis of the turret 94 with the motor casing 25 turned to bring the shaft 102 in 30 horizontal alignment with the shaft 44 at either side thereof, consequently bringing the path of movement of the slide 92 into the position B². It will be seen that with the axis of the turret 94 in the position C^{1a}, said 35 turret 94 may be rotated to bring the cutter bar 26 into the extreme upper horizontal position H^{1a}, that with said axis in the position c^{1a} said turret can be turned to bring the cutter bar into the extreme lower horizontal 40 position h^{1a}, that with said axis in either of the positions C^{1b} or c^{1b} said turret may be turned to bring said cutter bar into the intermediate position H¹, and that by proper adjustment of the main cutter head and of the 45 slide 92 said cutter bar may be caused to occupy any horizontal position between the positions H^{1a} and h^{1a}. Similarly, it will be seen that with the path of movement of the 50 slide 92 in the position B², the cutter bar can occupy the extreme vertical positions V^{2a} and v^{2a}, the central vertical position V², or any vertical position between the positions V^{2a} and v^{2a}. It will, moreover, be seen that with the 55 path of movement of the slide 92 in the position B¹ the turret 94 can be turned to bring the cutter bar into various offset vertical positions, those corresponding to the axis positions C^{1a} and c^{1a} being indicated by the characters V¹ and v¹; while with the 60 path of movement of said slide in the position B² said cutter bar may be caused to occupy various offset horizontal positions H² and h². In the latter connection it will be obvious that, by suitable adjustment of the 65 slide 92, said cutter bar can be brought into

any desired vertical position intermediate the positions V¹ or intermediate the positions v¹, or into any horizontal position intermediate the positions H² or intermediate the positions h². It will, of course, be understood that 70 with the cutter bar in any of the positions indicated, said cutter bar may swing about the axis of the hub 95 in a plane perpendicular to said axis to cut a kerf in the mine face in that plane. It will also be understood that, while certain horizontal and vertical 75 positions of the cutter bar are indicated in Fig. 15, the turret 94 may be turned upon its axis to bring said cutter bar into any desired inclined position tangent to a circle 80 drawn about the axis of said turret as a center, such circles drawn with respect to the several axis positions shown being indicated in Fig. 15 by the letters D^{1a}, D^{1b}, d^{1a}, d^{1b}, D^{2a}, D^{2b}, d^{2a}, and d^{2b}, and one such inclined 85 position with respect to the circle D^{1a} being shown at I. It will further be seen that, while certain angular positions of the motor casing 25 have been referred to (namely, those in which the path of movement of the 90 slide 92 occupies the vertical and horizontal positions B¹ and B²), said motor casing and main cutter head can be turned to any intermediate angular position to dispose the path 95 of movement of the slide 92 at an inclination, one such position being indicated by the line B³. It will be clear that in any such position the slide 92 can be adjusted to vary the distance of the axis of rotation 100 of the turret 94 from the main axis A (two such positions being indicated by C³ and c³, respectively), and that with said axis in any such position said turret can be rotated to bring the cutter bar into any position tangent to the corresponding circle D³ or d³, the 105 two extreme horizontal positions being indicated for illustrative purposes by the letters H³ and h³. It will thus be seen that the cutter bar may be adjusted into substantially 110 any position, and may be disposed at substantially any angle in any such position, so as to cut a kerf in substantially any plane within the range of the machine.

A machine arranged as above described is 115 capable of a wide variety of uses. For example, in the operation of entry driving, said machine may be used in accordance with the well known arcweld method illustrated in Fig. 12. In accordance with this method, the truck having been propelled into a suitable 120 position in proximity to the face to be cut and brought to rest therein, the pin 154 is removed and the hand wheel 143 operated to throw in the clutch 134 and cause the cutter bar 26 to be quickly swung into the dotted line position F. The clutch 134 is then released and the cutter bar locked in this 125 position by the pin 154, after which the lever 86 is operated to throw in the clutch 79 to cause the machine to be fed toward the face 130

at slow speed until the cutter bar is brought into the position shown in full lines in Fig. 12, thereby producing the sumping cut. The clutch 79 is then released and the lever 86 operated to engage the clutch 80 (the pin 88 having been inserted to lock the head 53 to the sleeve 54), thereby holding the machine in stationary position. The pin 154 is then removed and the hand wheel 143 operated to engage the clutch 133, thereby causing the cutter bar to be swung slowly from the position shown in full lines into the dotted line position G. Finally, the pin 154 is again inserted to lock the cutter bar (the clutch 133 having been released), and the lever 83 operated to engage the clutch 78, thereby causing the machine to be moved slowly rearwardly and bringing the cutter bar into the dotted line position K to complete the cut. Thereafter, by suitable operation of the hand wheel 143, the cutter bar may be swung into a substantially central position, the lever 83 operated to engage the clutch 77, and the controller 38 operated to reverse the motor, whereupon the machine will be caused to back out of the entry, whence it may be propelled to a different part of the mine.

It will be seen that in operating as above described, the machine can be caused to insert, for example, either horizontal kerfs, as illustrated in Fig. 13, or vertical kerfs as illustrated in Fig. 14, and that these kerfs may be cut in substantially any plane within the range of the machine. Thus, for example, in cutting horizontal kerfs said machine may be used for undercutting, as illustrated in Fig. 16, for topcutting, as illustrated in Fig. 13, or for inserting a substantially horizontal kerf in any intermediate plane. It will also be seen that by a suitable adjustment of the hand wheel 35, the plane of the cutter bar may be adjusted about a transverse horizontal axis in order to cause the kerf to be cut at a slight angle to the horizontal in the direction of travel of the machine, as indicated in Fig. 16.

In general, it will be seen that a machine has been provided wherein the cutter bar is capable of being adjusted in various positions about both transverse and longitudinal horizontal axes, and that said cutter bar is further adjustable toward and from said last named axis, and angularly about a third axis parallel to said longitudinal axis, into any desired position within the range of operation of the machine.

In addition to operating in accordance with the arcwall method, as above described, the machine is also capable of use as a mounted longwall machine, as diagrammatically illustrated in Figs. 17 and 18. When so operated, the controlling lever 83 may be adjusted to engage the clutch 77, causing the machine to be propelled at relatively high speed to the end of the face to be cut. There-

after, the lever 83 may be operated to disengage the clutch 77, and the lever 86 operated to engage the clutch 80 to lock the truck in position on the track. The hand wheel 143 may then be operated to engage the clutch 133, thereby causing the cutter bar 26 to be swung into either of the positions shown in Fig. 17 (depending upon the position of the face to be cut with respect to the track) to produce the sumping cut. The hand wheel 143 is then operated to release the clutch 133, the locking pin 154 inserted to lock the cutter bar in position, and the lever 83 operated to engage the clutch 78, thereby causing the truck to move slowly rearwardly along the trackway and the cutter bar to cut the desired kerf in the face.

Should it be desired to cut such a kerf in a plane inclined to the plane of the trackway, as in following a pitching seam, the cutter bar 26 may be brought to the desired angle and vertical position by an angular adjustment of either the main head or the turret 94 and a suitable adjustment of the slide 92, as indicated in Fig. 18.

While several uses of the machine have thus been indicated, these uses by no means exhaust its possibilities, since, by reason of its wide adjustability, convenient and flexible control, high power, and sturdy construction, many other ways in which the same may be utilized to great advantage will be readily recognized by those skilled in the art.

For the sake of conciseness I shall employ the term "turret" in the appended claims, since this word both aptly and concisely defines certain structural elements of my improved mechanism.

In the appended claims the terms "longitudinal" and "transverse" are used, with reference to axes, in the sense of extending longitudinally of the machine as a whole, or transversely of the machine as a whole, unless otherwise plainly indicated in the claims themselves.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, in combination, a motor, a support rectilinearly movable towards and from a working face during cutting operation of the machine, a motor casing in which said motor is disposed rotatably mounted on said support for rotation about an axis parallel to the direction of rectilinear movement of said support during cutting, and plane kerf cutting means driven by said motor carried by said motor casing and ad-

justable with respect to said casing towards and from the axis of the latter.

2. In a mining machine, in combination, a motor, a support rectilinearly movable towards and from a working face during cutting operation of the machine, a motor casing in which said motor is disposed rotatably mounted on said support for rotation about an axis parallel to the direction of rectilinear movement of said support during cutting, plane kerf cutting means driven by said motor carried by said motor casing, and means for adjusting said kerf cutting means angularly in a plane parallel to said axis of said casing and also bodily towards and from the latter.

3. In a mining machine, in combination, a motor, a support, a motor casing in which said motor is disposed, said motor casing being mounted on said support for rotation about an axis coinciding with the axis of the motor, and cutting means driven by said motor carried by the motor casing and movable to a position in which its plane contains the axis 25 of the motor.

4. In a mining machine, in combination, a motor, a support, a motor casing in which said motor is disposed, said motor casing being mounted on the support for rotation about an axis coinciding with the axis of the motor, and cutting means carried by the motor casing and adjustable about an axis parallel to, but off set from, the axis of the casing.

5. In a mining machine, in combination, a support, a motor casing rotatably mounted thereon for adjustment about a horizontal axis, and cutting means carried by said motor casing and adjustable by rotation of said casing to cut in horizontal or in vertical planes, 35 said cutting means being adjustable with respect to said casing and operative in any given position of said casing to cut a series of kerfs disposed in intersecting planes each of which is parallel to said horizontal axis.

45 6. In a mining machine, in combination, a support, a motor casing rotatably mounted thereon about a longitudinally disposed horizontal axis, and cutting means carried by said motor casing, said cutting means being adjustable with respect to said casing and operative in any given position of said casing to cut a series of kerfs disposed in intersecting planes successive movements of said support toward a working face.

55 7. In a mining machine, a support, a mounting rotatable thereon about a longitudinal horizontal axis, ways disposed on said mounting, a carriage movable along the ways, cutting means including circulating cutting elements moving in a plane orbit, said cutting means being adjustably mounted on said carriage for adjustment into a plurality of positions in each of which a homologous axis of said orbit may coincide with a distinct ele-

ment of a surface of revolution whose axis is parallel to said horizontal axis.

8. In a mining machine, a support, a mounting rotatable thereon about a longitudinal axis, ways disposed thereon, a carriage movable along the ways, cutting means moving in an orbit and mounted on said carriage for adjustment into a plurality of positions in each of which a homologous axis of said orbit may coincide with a distinct element of a surface of revolution whose axis is parallel to said longitudinal axis, and said cutting means being also adjustable with respect to said carriage whereby said cutting means may be swung to cause said homologous axis to make angles with said elements in planes tangent to said surface at said elements.

9. In a mining machine, a support, ways mounted on said support for rotation about an axis perpendicular to the plane of said ways, a carriage movable along said ways, cutting means movable in an orbit and adjustably mounted on said carriage for movement into a plurality of positions in which the major axis of said orbit will coincide with elements of a cylindrical surface whose axis is parallel to a line which is parallel to said first mentioned axis, and means for varying the distance between the axis of said cylinder and the first mentioned axis.

10. In a mining machine, a support, means for feeding the same during cutting, ways mounted on said support for rotation about an axis perpendicular to the plane of said ways and parallel to the direction of movement of said support, a carriage movable along said ways; a motor, means driven by said motor for moving said carriage in said ways, and cutting means carried by said carriage and movable in a plane orbit, said cutting means being mounted on said carriage for swinging movement in a series of planes tangent to a cylinder whose axis is perpendicular to the plane of said ways.

11. In a mining machine, a support, means for feeding the same during cutting, ways mounted on said support for rotation about an axis perpendicular to the plane of said ways and parallel to the direction of movement of said support, a carriage movable along said ways, a motor, means driven by said motor for moving said carriage in said ways, cutting means carried by said carriage and movable in a plane orbit, said cutting means being mounted on said carriage for swinging movement in a series of planes tangent to a cylinder whose axis is perpendicular to the plane of said ways, and means for tilting said support about a horizontal axis perpendicular to a vertical plane including said first mentioned axis.

12. In a mining machine, a support, a turntable thereon having a horizontal axis of rotation, ways on said turntable, a carriage movable along said ways, a swinging cutter bar

mounted on said carriage, and means for adjusting said carriage on said ways and said bar bodily relative to said carriage whereby said bar may swing in the same plane when said ways are in different angular positions on said support.

13. In a mining machine, a support, a pair of ways mounted on said support for rotation relative thereto about a horizontal axis perpendicular to the plane of said ways, a carriage movable along said ways, a swinging cutter bar mounted on said carriage for swinging movement in planes perpendicular to the plane of movement of said carriage, and means including a rotatably mounted prime mover and operative connections therewith, whereby said carriage may be adjusted on said ways and said bar may be adjusted on said carriage so that said bar may swing in a plane including the axis about which said ways are rotated and in one position have its axis alined therewith.

14. In a mining machine, a support, ways carried by said support for rotation about an axis perpendicular to the plane of said ways, a carriage movable along said ways, a swinging cutter bar mounted on said carriage and swinging in a plane perpendicular to the plane of said ways, and means for adjusting said bar as a whole on said carriage, said carriage on said ways, and said ways on said support whereby a plurality of kerfs may be cut intersecting in a line constituting a continuation of the axis about which said ways are rotatable.

15. In a mining machine, in combination, a support, a motor, a motor casing in which said motor is disposed rotatably mounted on said support, and cutting means carried by said motor casing, said motor casing being rotatable on an axis extending longitudinally of the machine and said cutting means being adapted to cut in planes substantially parallel to the axis of rotation of said motor casing and being adjustable by said motor bodily toward and from said axis.

16. In a mining machine, in combination, a support, a motor casing rotatably mounted thereon upon a horizontal axis, a motor in said casing having a rotating element whose axis of rotation is parallel to a line parallel to said horizontal axis, a cutter bar, means for supporting said cutter bar from said motor casing, said supporting means permitting said cutter bar to swing about an axis transverse to the axis of rotation of said motor casing, and means for moving said support in a direction parallel to said first mentioned axis to effect the cutting of a plane kerf.

17. In a mining machine, in combination, a support, a motor, a motor casing rotatably mounted thereon for rotation about an axis coincident with the axis of rotation of said motor, power means for rotating said motor

casing about its axis, and cutting means carried by said motor casing.

18. In a mining machine, in combination, a support, a motor, a motor casing in which said motor is disposed rotatably mounted 70 upon said support for rotation about an axis concentric with the motor axis, means actuated by said motor for rotating said casing, and cutting means carried by said casing and actuated by said motor.

19. In a mining machine, in combination, a support, a motor casing rotatably mounted thereon, cutting means carried by said motor casing, a gear carried directly by said motor casing, a pinion cooperating with said gear to rotate said casing, a motor in said casing for actuating said cutting means, and means actuated by said motor for rotating said pinion.

20. In a mining machine, in combination, 85 a support, a motor, a motor casing in which said motor is disposed, said motor casing being rotatably mounted on said support for rotation about the axis of said motor, and cutting means carried by said motor casing 90 and angularly adjustable thereon into planes perpendicular to angularly disposed radii extending from the axis of the motor.

21. In a mining machine, in combination, a support, a motor having a rotatable power 95 shaft, a motor casing enclosing said motor and mounted on said support for rotation on an axis coincident with the axis of said shaft, a turret rotatably mounted on said casing, and a cutter carried by said turret.

22. In a mining machine, in combination, a support, a motor having a rotatable power shaft, a motor casing enclosing said motor and mounted on said support for rotation on an axis coincident with the axis of said shaft, 105 a turret rotatably mounted on said casing, and a cutter bar mounted on said turret to swing about an axis transverse to the axis of said turret.

23. In a mining machine, in combination, 110 a support, a motor having a rotatable power shaft, a motor casing enclosing said motor and mounted on said support for rotation on an axis coincident with the axis of said shaft, and cutting means carried by said motor 115 casing and angularly adjustable thereon about an axis parallel to the axis of rotation of said casing.

24. In a mining machine, in combination, a support, a motor casing rotatably mounted 120 thereon for rotation on an axis which passes through the casing, a turret mounted on said casing for rotation about an axis parallel to the axis of rotation of said casing, and a cutter bar mounted on said turret to swing 125 about an axis transverse to said first named axes.

25. In a mining machine, in combination, a support, a motor having a power shaft, a motor casing in which said motor is disposed 130

- rotatably mounted on said support for adjustment about the axis of rotation of the motor shaft, and a cutter mounted on said casing for rectilinear adjustment in a direction transverse to the axis of rotation of said casing.
26. In a mining machine, in combination, a support, a second support rotatably mounted thereon for rotation about a horizontal axis, a carriage slidably mounted on said second support for movement transverse to the axis of rotation thereof, and plane kerf cutting means carried by and bodily adjustable relative to said carriage about an axis parallel to said horizontal axis and outside the cutting means and operative to cut kerfs parallel to said horizontal axis.
27. In a mining machine, in combination, a support, a motor having a power shaft, a motor casing mounted on said support for adjustment about an axis coincident with that of said power shaft, a carriage slidably mounted on said motor casing for movement transverse to the axis of rotation thereof, and cutting means carried by and adjustable relative to said carriage.
28. In a mining machine, in combination, a horizontally movable support, a second support rotatably mounted thereon, for rotation about an axis parallel to the path of said first mentioned support, a carriage slidably mounted on said second support for movement transverse to the axis of rotation thereof, power means for sliding said carriage on said second support, a cutter bar mounted on said carriage to swing about a pivot disposed on said carriage and arranged transverse to the axis of rotation of said second support, and means to adjust said bar pivot on said carriage.
29. In a mining machine, in combination, a support, a second support rotatably mounted thereon, a carriage slidably mounted on said second support for movement transverse to the axis of rotation thereof, a cutter bar mounted on said carriage to swing about an axis disposed on said carriage and arranged transverse to the axis of rotation of said second support, and a single means selectively operative to rotate the said second support and to move said carriage.
30. In a mining machine, in combination, a support, a second support rotatably mounted thereon, a carriage slidably mounted on said second support for movement transverse to the axis of rotation thereof, a cutter bar mounted on said carriage to swing about an axis disposed on said carriage and arranged transverse to the axis of rotation of said second support, and a single means selectively operative to rotate said second support and to swing said cutter bar.
31. In a mining machine, in combination, a support, a second support rotatably mounted thereon for rotation on a horizontal axis, a carriage slidably mounted on said second support for movement transverse to the axis of rotation thereof, a cutter bar mounted on said carriage to swing about an axis disposed on said carriage and arranged transverse to the axis of rotation of said second support, and a single means selectively operative to move said carriage and to swing said cutter bar.
32. In a mining machine, in combination, a support, a motor, a casing for said motor mounted on said support for adjustment on an axis coincident with the axis of the motor shaft, a carriage slidably mounted on said casing for movement transverse to the axis of rotation thereof, cutting means carried by said carriage, and continuously operative driving connections between said motor and cutting means.
33. In a mining machine, the combination with a plane kerf cutter, of supporting means therefor adapted to permit independent angular motor power adjustment thereof about a plurality of parallel axes, said cutter being mounted on said supporting means for rectilinear bodily adjustment in a direction transverse to said axes.
34. In a mining machine, the combination with a cutter, of supporting means therefor adapted to permit angular adjustment thereof about a plurality of parallel axes parallel to the plane of said cutting mechanism, said cutter being mounted on said supporting means for rectilinear adjustment in a direction transverse to said axes and said supporting means being movable in a direction parallel to said axes to effect cutting by said cutter.
35. In a mining machine, the combination with a cutter bar, of supporting means therefor adapted to permit angular adjustment thereof about a plurality of parallel axes, said cutter bar being mounted on said supporting means to swing about an axis transverse to said first named axes, and being capable of rectilinear adjustment in a direction transverse to said first named axes, said supporting means being movable in a direction parallel to said axes to effect cutting by said cutter.
36. In a mining machine, in combination, a support, a motor casing rotatably mounted thereon, a carriage slidably mounted on said motor casing for movement transverse to the axis of rotation thereof, a turret rotatably mounted on said carriage, and a cutter carried by said turret and adjustable to a plurality of angular positions relative thereto.
37. In a mining machine, in combination, a support, a motor casing rotatably mounted thereon, a motor therein constituting the prime mover for said machine, a carriage slidably mounted on said motor casing for movement transverse to the axis of rotation thereof, a turret rotatably mounted on said carriage, a second turret rotatably mounted

- on said first named turret, and a cutter bar carried by said second turret.
38. In a mining machine, in combination, a motor, a cutter bodily adjustable with respect to said motor, and transmission mechanism for actuating and adjusting said cutter from said motor including a driving element connected with said motor, a driven element adjustable with respect to said driving element bodily towards and away from the latter and operatively connected with said cutter, a single bodily movable transmission element connecting said driving and driven elements and offset from the axis of the driving elements, and means for maintaining said element, and means for maintaining said transmission element in engagement with both of said first named elements in all positions of adjustment of said driven element.
39. In a mining machine, in combination, a support, a motor thereon, a carriage slidably mounted on said support, cutting means on said carriage, and transmission mechanism for actuating and adjusting said cutting means from said motor including a driving element connected with said motor, a driven element movable with said carriage bodily towards and away from said driving element and connected with said cutter, a single transmission element connecting said driving and driven elements, and offset from the axis of the driving element, and means for maintaining said transmission element in engagement with both of said first named elements in all positions of said carriage.
40. In a mining machine, in combination, a motor, a cutter adjustable with respect to said motor, and transmission mechanism for actuating and adjusting said cutter from said motor including a pinion on the motor shaft, a gear adjustable with respect to said pinion bodily towards and away from the latter and operatively connected with said cutter, a second gear connecting said pinion with said first named gear, means for maintaining said second gear in mesh with both said pinion and said first named gear in all positions of adjustment of said first named gear, and means operative at will for preventing rotation of said first mentioned gear to cause bodily movement thereof and of said cutter.
41. In a mining machine, in combination, a motor, a cutter adjustable with respect to said motor, and transmission mechanism for actuating and adjusting said cutter from said motor including a driving element connected with said motor, a driven element adjustable with respect to said driving element bodily towards and away from the latter and operatively connected with said cutter, a movable transmission element connecting said driving and driven elements, means for causing said transmission element to maintain fixed distances from the axes of said driving and driven elements when said driven element is adjusted, and means cooperating with said first mentioned element to cause the coaction of said several elements to cause translation of said first mentioned element.
42. In a mining machine, in combination, a motor, a cutter adjustable with respect to said motor, and transmission mechanism for actuating and adjusting said cutter from said motor including a driving element connected with said motor, a driven element adjustable with respect to said driving element and operatively connected with said cutter, a movable transmission element connecting said driving and driven elements, a link connecting said driven and transmission elements, and an annular slide arranged concentric with said driving element by which said transmission element is carried.
43. In a mining machine, in combination, cutting means, means for adjusting the same to cut in different positions in which kerfs parallel to planes making angles with each other will be cut, means for locking said adjusting means against operation, means for moving said cutting means with respect to the work during the cutting operation, a common actuator for said adjusting means and moving means, and transmission devices between said actuator and said adjusting and moving means operable as a brake upon said moving means when said adjusting means is locked.
44. In a mining machine, in combination, a support, a motor casing rotatably mounted thereon, cutting means carried by said motor casing, means for locking said motor casing against rotation, means for moving said support, a common actuator for said rotating means and moving means, and transmission devices between said actuator and said rotating and moving means operable as a brake upon said moving means when said motor casing is locked against rotation.
45. In a mining machine, in combination, a truck, cutting means thereon, means for adjusting said cutting means to cut in different positions parallel to angularly related planes, means for locking said adjusting means against operation, means for propelling said truck, a common actuator for said adjusting means and propelling means, and transmission devices between said actuator and said adjusting and propelling means operable as a brake for said truck when said adjusting means is locked.
46. In a mining machine, in combination, cutting means, means for adjusting the same to cut in different angularly related planes, means for moving said cutting means with respect to the work during the cutting operation, a shaft, transmission devices for actuating said moving means, means for operatively connecting said transmission devices to said shaft, a transmission member operatively connected with said adjusting means,

- means for operatively connecting said transmission member to said shaft, and means for locking said transmission member against operation.
47. In a mining machine, in combination, a support, ways thereon rotatable about a horizontal axis, a carriage slidably mounted on said ways, power means for adjusting said carriage on said ways including a plurality of rotating elements, said rotating elements rotating only on axes perpendicular to the plane of said ways, cutting means carried by said carriage and angularly adjustable relative thereto, and mean for locking said carriage to said ways.
48. In a mining machine, in combination, a support, a second support rotatably mounted thereon for rotation on a horizontal axis, ways on said second support, a carriage slidably mounted on said ways for movement transverse to the axis of rotation of said second support, cutting means including a plane cutter bar carried by said carriage and angularly adjustable relative thereto, power means for moving said cutting means on said carriage, and means for locking said carriage to said ways.
49. In a mining machine, in combination, a support, ways thereon rotatable about a horizontal axis and having notched flanges, a carriage slidably mounted on said ways, cutting means carried by said carriage, and a pin removably carried by said carriage and engaging the notches in said flanges for locking said carriage to said ways.
50. In a mining machine, in combination, a support, vertical ways thereon, a carriage slidably mounted on said ways for sliding movements in vertical planes, a movable cutter carried by said carriage and disposed in a plane perpendicular to the plane of movement of said carriage, and power operated mechanism alternatively operative to move said carriage or to move said cutter thereon while said carriage remains stationary.
51. In a mining machine, in combination, a support, vertical ways thereon, a carriage slidably mounted on said ways for sliding movements in vertical planes, a movable cutter carried by said carriage and disposed in a plane perpendicular to the plane of movement of said carriage, mechanism alternatively operative to move said carriage or to move said cutter thereon while said carriage remains stationary, and devices for locking said cutter against movement on said carriage and for locking said carriage against movement on said ways.
52. In a mining machine, in combination, a support, ways thereon rotatable about a substantially horizontal longitudinal axis, a carriage slidably mounted on said ways, a turret rotatably mounted on said carriage, a cutter carried by said turret, and mechanism alter-
- natively operative to move said carriage or to rotate said turret thereon.
53. In a mining machine, in combination, a support, ways thereon, rotatable about a horizontal axis, a carriage slidably mounted on said ways, a turret rotatably mounted on said carriage, a cutter carried by said turret, and common power mechanism alternatively operative to move said carriage or to rotate said turret thereon.
54. In a mining machine, in combination, a support, ways rotatably mounted thereon, for adjustment about a horizontal axis, a carriage slidably mounted on said ways, a turret rotatably mounted on said carriage, a movable cutter on said turret and common power operated mechanism selectively operative to move said carriage, to rotate said turret thereon, or to move said cutter on said turret.
55. In a mining machine, a truck, a motor at the front end thereof and having an enclosing casing rotatable about a horizontal axis, cutting mechanism disposed in a plane parallel to said axis and operatively connected to the front end of said motor and carried on said casing, and casing rotating mechanism carried on said truck and operatively connected to for driving the rear end of said motor.
56. In a mining machine, a truck, a motor at the front end thereof and having a casing rotatable about the axis of the motor, cutting mechanism operatively connected to the front end of said motor and carried on said casing, and casing rotating mechanism carried on said truck and operatively connected to the rear end of said motor.
57. In a mining machine, a truck, a motor at the front end thereof and having a casing rotatable about an axis extending longitudinally of said motor, cutting mechanism operatively connected to the front end of said motor and carried on said casing, and casing rotating mechanism carried on said truck and operatively connected to the rear end of said motor.
58. In a mining machine, a truck, a motor thereon having a casing rotatable about the axis of said motor, cutting mechanism driven by said motor and carried on said casing, casing rotating mechanism on said truck operatively connectable to said motor, and truck driving mechanism on said truck operatively connectable to said motor.
59. In a mining machine, a truck, a motor thereon having a rotatable casing, cutting mechanism driven by said motor and carried on said casing, casing rotating mechanism on said truck operatively connectable to said motor, truck driving mechanism on said truck operatively connectable to said motor, and coaxially disposed frictional controlling mechanisms for controlling said casing rotating and truck driving mechanisms.

- 5 60. In a mining machine, a truck, a motor thereon having a rotatable casing, cutting mechanism driven by said motor and carried on said casing, casing rotating mechanism on said truck operatively connectible to said motor, truck driving mechanism on said truck operatively connectible to said motor, coaxially disposed driving members for said two last mentioned mechanisms, and frictional controlling mechanisms operable to effect operation of said driving members.
- 10 61. In a mining machine, a truck, a motor thereon having a casing rotatable about the axis of said motor, cutting mechanism driven by said motor and carried on said casing, truck driving mechanism on said truck operatively connectible to said motor, and casing rotating mechanism on said truck operatively connectible to said truck driving mechanism.
- 15 62. In a mining machine, a truck, a motor carried thereon and having a casing rotatable about the axis of said motor, cutting mechanism carried by one end of said casing and operatively connected to one end of said motor, and mechanism on said truck operatively connected between one end of said motor and one end of said casing for rotating the latter.
- 20 63. In a mining machine, a truck, a motor carried thereon and having a casing rotatable about the axis of said motor, cutting mechanism carried by one end of said casing and operatively connected to the same end of said motor, and mechanism on said truck operatively connected between the other end of said motor and the other end of said casing for rotating the latter.
- 25 64. In a mining machine, a truck, a motor carried thereon and having a casing rotatable about a longitudinal axis, cutting mechanism carried by one end of said casing and operatively connected to one end of said motor, and mechanism driven from one end of said motor and operatively connected to the other end of said casing for rotating the latter.
- 30 65. In a mining machine, a truck, a motor carried thereon and having a rotatable casing, cutting mechanism driven from said motor and carried by one end of said casing, mechanism driven from the opposite end of said motor and operatively connected to the opposite end of the casing for rotating the latter, and truck driving mechanism connectable at will with the latter end of said motor.
- 35 66. In a mining machine, a truck, a motor carried thereon having at the opposite ends of its power shaft toothed driving elements, angularly adjustable cutting mechanism carried on said truck, operative connections between the same and one end of said motor, mechanism driven from the other end of said motor for rotating said cutting mechanism, truck driving mechanism driven from the last mentioned end of said motor, and mechanism including a plurality of friction clutches operable to control said cutting mechanism, rotating mechanism, and said truck driving mechanism.
- 40 67. In a mining machine, a truck, a motor thereon having a rotatable casing, cutting mechanism carried on one end of said casing and driven by said motor, casing rotating driving connections between the opposite end of said motor and said casing including controlling mechanism, truck driving mechanism, and means for selectively operating said controlling mechanism to rotate said casing in opposite directions or drive said truck driving mechanism in opposite directions.
- 45 68. In a mining machine, a truck, a motor thereon having a rotatable casing, cutting mechanism carried on one end of said casing and driven by said motor, casing rotating driving connections between the opposite end of said motor and said casing including controlling mechanism, truck driving mechanism, and means for selectively operating said controlling mechanism to rotate said casing in opposite directions or drive said truck driving mechanism in opposite directions, or to operate either at different speeds.
- 50 69. In combination, a support, a mining machine thereon having a pivoted cutter bar rotatable bodily about a horizontal axis outside said bar, and means including a motor having a casing rotatable with said bar and operative to effect swinging movement of said bar about its pivot and bodily movement of said bar about said axis.
- 55 70. In combination, a support, a mining machine thereon having a pivoted cutter bar rotatable bodily about a horizontal axis outside said bar, and means including and actuated by a motor having a casing rotatable with said bar for effecting swinging movement of said bar about its pivot and feeding movement of said bar and support towards a working face.
- 60 71. In combination, a support, a mining machine thereon having a pivoted cutter bar rotatable bodily about a horizontal axis outside said bar, means for tilting said axis, and means including a motor having a casing rotatable with said bar about said axis for effecting bodily movement of said bar about said axis and bodily movement of said bar and support towards a working face.
- 65 72. In a mining machine, in combination, a support, a casing rotatable on said support about a horizontal axis and containing the prime mover of said machine, a pair of ways extending transversely of said casing, a carriage slidable in said ways, a plane cutter carried on said carriage upon a pivot lying constantly in a plane parallel to the plane of said ways, and means for adjusting said last mentioned pivot about an axis parallel to said first mentioned axis.
- 70 73. In a mining machine, in combination, a support, a casing rotatable on said support about a horizontal axis and containing the

- prime mover of said machine, a pair of ways extending transversely of said casing, a carriage slideable in said ways, a plane cutter bar carried on said carriage upon a pivot lying constantly in a plane parallel to the plane of said ways, means for adjusting said last mentioned pivot about an axis parallel to said first mentioned axis, and means for moving said carriage in said ways while the latter remain stationary and with the plane of said bar making angle to a horizontal plane.
74. In a mining machine, in combination, a support, a casing rotatable on said support about a horizontal axis, a pair of ways extending transversely of said casing, a carriage slideable in said ways, a plane cutter bar mounted on said carriage upon a pivot lying constantly in a plane parallel to the plane of said ways, means for adjusting said last mentioned pivot about an axis parallel to but offset from said first mentioned axis, and means for moving said carriage in said ways while the latter remain stationary and with the plane of said bar making any angle to a horizontal plane.
75. In a mining machine in combination, a support, a second support rotatable thereon about a horizontal axis, means for moving said supports simultaneously at an equal rate in a direction parallel to said axis during cutting, a pair of parallel ways disposed in a plane to which said axis is perpendicular, a carriage movable on said ways, a cutter bar having a pivot-mounting on said carriage whereon it may swing in planes parallel to said axis, said pivot-mounting being adjustable on said carriage to permit said bar to swing in vertical or horizontal planes while said carriage remains stationary in said ways, and means for moving said carriage along said ways while said bar lies in a plane parallel to the direction of said ways.
76. In a mining machine, in combination, a portable base, means for effecting rectilinear movement thereof toward and from a working face, a plane kerf cutter, means for driving said kerf cutter including a motor which has a rotatable casing and whose driving shaft extends constantly longitudinally of said base, the plane of said kerf cutter being parallel to said shaft, and means operated by said motor for changing the distance between said plane and said shaft.
77. In a mining machine, in combination, a portable base, means for effecting rectilinear movement thereof toward and from a working face, a plane kerf cutter, means for driving said kerf cutter including a motor which has a rotatable casing and whose driving shaft extends constantly longitudinally of said base, the plane of said kerf cutter being parallel to said shaft, and means operated by said motor for changing the angular relation of said plane to a horizontal plane in which the axis of said shaft lies.
78. In a mining machine, in combination, a portable base, means for effecting rectilinear movement thereof toward and from a working face, a plane kerf cutter, means for driving said kerf cutter including a motor which has a rotatable casing and whose driving shaft extends constantly longitudinally of said base, the plane of said kerf cutter being parallel to said shaft, and means operated by said motor for changing the angle between said plane and a horizontal plane including the axis of said shaft and the distance between said plane and said axis.
79. In a machine of the nature described, the combination of a cutting mechanism supporting means having a neck seated rotatably in a bearing, an elongated cutting mechanism hinged to said support to permit movement of said mechanism toward and from the axial line of said neck while said cutting mechanism remains parallel to said line and to swing in a plane which is parallel to said line, operator-controlled, power-actuated yielding transmission mechanism for slowly swinging said cutting mechanism in said plane, and a neck shaft extending through said neck and arranged in operative relation with the cutting mechanism for actuating said cutting mechanism, substantially as described.
80. In a machine of the nature described, the combination of a cutting mechanism supporting means having a neck seated rotatably in a bearing, an elongated cutting mechanism hinged to said support to permit movement of said mechanism toward and from the axial line of said neck while said cutting mechanism remains parallel to said line and to swing in a plane which is parallel to said line, operator-controlled, power-actuated yielding transmission mechanism for slowly swinging said cutting mechanism in said plane, means for rotating said neck, and transmission means extending through said neck for actuating said cutting mechanism, substantially as described.
81. In a machine of the nature described, the combination of a cutting mechanism supporting means having a neck seated rotatably in a bearing, an elongated cutting mechanism hinged to said support to permit movement of said mechanism toward and from the axial line of said neck while said cutting mechanism remains parallel to said line and to swing in a plane which is parallel to said line, operator-controlled, power-actuated yielding transmission mechanism for slowly swinging said cutting mechanism in said plane, means for rotating said neck, and a neck shaft extending through said neck and arranged in operative relation with the cutting mechanism for actuating said cutting mechanism, substantially as described.
82. In a machine of the nature described, the combination of a rotatable neck which is in a bearing which is fixed relative to the

- machine body and is horizontal and parallel to the machine path, operator-controlled, power-driven means for actuating said neck, an elongated cutting tool, and members supported by said neck and supporting said cutting tool parallel to the neck axis and for bodily movement toward and from the axial line of the neck and for swinging in a plane which is parallel to said axis, operator-controlled, power-actuated yielding mechanism for swinging said cutting tool in said plane, and a neck shaft in said neck, and means operatively connecting said neck shaft and said cutting tool for actuating said cutting tool for cutting, substantially as described. 70
83. In a machine of the nature described, the combination of a rotatable neck which is in a bearing which is fixed relative to the machine body and is horizontal and parallel to the machine path, operator-controlled, power-driven means for actuating said neck, a cutting tool, articulated members supported on said neck and having hinge lines extending in diverse directions and said members being adapted to support the cutting tool at varying distances from the axial line of the neck and to swing the tool in a plane which is parallel to said axis, operator-controlled, power-actuated yielding mechanism for swinging said tool in said plane whereby the cutting tool may be carried through an orbital path by the rotation of said neck and the radius of said orbital path may be varied by varying the distance at which said members support said tool from the axial line of the neck and said tool may be held in a line which is parallel to or transverse to the neck axis, a neck shaft in said neck, and means operatively connecting said shaft and the cutting tool for actuating said tool, substantially as described. 85
84. In a machine of the nature described, the combination of a tool support rotatable on a horizontal axis, operator-controlled, power-driven mechanism for effecting rotation of said support, a cutting tool, a plurality of articulated members supporting said tool on said support for movement toward and from the axial line of said support and for swinging the tool in a plane parallel to said axial line, operator-controlled, power-actuated yielding transmission mechanism for swinging the cutting tool in said plane, and means for actuating said cutting tool, substantially as described. 90
85. In a machine of the nature described, the combination of a tool support rotatable on a horizontal axis which is fixed relative to the body of the machine, operator-controlled, power-driven mechanism for effecting rotation of said support, a cutting tool, members supporting said tool on said support for movement toward and from the axial line of said support and for swinging the tool in a plane which is parallel to said axis, operator-controlled, power-driven, yielding means for effecting said swinging movement, and means for actuating said tool for cutting, substantially as described. 95
- a plane parallel to said axial line, operator-controlled, power-actuated yielding transmission mechanism for swinging the cutting tool in said plane, and means extending through and along the axis of said support for actuating said cutting tool, substantially as described. 100
86. In a machine of the nature described, the combination of a tool support rotatable on a horizontal axis, mechanism for effecting rotation of said support, a cutting tool, members supporting said tool on said support for movement toward and from the axial line of said support for swinging the tool in a plane parallel to said axial line, mechanisms on said rotatable support for actuating said supporting members for moving said tool toward and from the axial line of the rotary support and operator-controlled, power-driven, yielding transmission mechanism for swinging the tool in a plane parallel to said axial line, and means for actuating said cutting tool, substantially as described. 105
87. In a machine of the nature described, the combination of a rotary body, an elongated cutting tool, means intervening said supporting body and the cutting tool for carrying the cutting tool parallel to said axial line for orbital movement around said line and from and toward and into said line and for yieldingly swinging the tool in a plane parallel to the axial line of the rotary body, substantially as described. 110
88. In a machine of the nature described, the combination of a rotary supporting body on an axial line which is approximately coincident with the longitudinal center line of the machine, an elongated cutting tool carried parallel to said axial line for orbital movement around said line and from and toward and into said line and to yieldingly swing in a plane which is parallel to said axial line, substantially as described. 115
89. In a machine of the nature described, the combination of a rotary supporting body, an elongated cutting tool, means intervening said supporting body and said cutting tool for carrying the latter for orbital movement around said line and from and toward and into said line and to yieldingly swing in planes parallel to the axial line of said supporting body, substantially as described. 120
90. In a machine of the nature described, the combination of a rotatable support which is horizontal and parallel to the machine path, an elongated cutting tool, members supported by said support and supporting said cutting tool for movement from and toward and into the axial line of the rotatable support and for swinging the tool in a plane which is parallel to said axis, operator-controlled, power-driven, yielding means for effecting said swinging movement, and means for actuating said tool for cutting, substantially as described. 125

91. In a machine of the nature described, the combination of an elongated cutting tool, means for supporting said tool parallel to the machine path and to carry said tool in such 5 parallel relation through orbital paths which are concentric to the middle longitudinal line of the machine and which range in diameter from zero to the largest, which is of larger diameter than the transverse dimensions of 10 the machine, and to yieldingly swing said tool in planes which are parallel to the axial line of the orbital paths, and means for actuating said cutting tool for cutting, substantially as described. 15
92. Mining apparatus including a frame supporting at one end thereof cutting mechanism, and means for effecting propulsion of 20 said apparatus during cutting in a path parallel to the major dimension of said frame including at the end of the frame remote from the cutting mechanism a driving member rotatable upon a horizontal axis extending longitudinally of the frame, and driving 25 means for the cutting mechanism and the member including a motor disposed between the cutting mechanism and said member on the frame, the driving means for the member including mechanism operative to effect plural predetermined speed drive thereof. 30
93. Mining apparatus including a frame supporting at one end thereof cutting mechanism, and means for effecting propulsion of 35 said frame during cutting in a path parallel to the major dimension of said frame including at the end of said frame remote from said cutting mechanism a driving member rotatable upon a horizontal axis extending longitudinally of said frame, and driving 40 means for said cutting mechanism and said member including a motor disposed between said cutting mechanism and said member on said frame and having a power shaft parallel to the axis of rotation of said member, the 45 driving means for the member including means for effecting plural predetermined speed drive thereof. 50
94. Mining apparatus including a frame supporting at one end thereof cutting mechanism, and means for effecting propulsion of 55 said apparatus during cutting in a path parallel to the major dimension of said frame including at the end of said frame remote from said cutting mechanism a driving member rotatable upon a horizontal axis extending 60 longitudinally of said frame, and driving means for said cutting mechanism and said member including a motor disposed between said cutting mechanism and said member on 65 said frame, the driving means for said member including gearing for effecting drive thereof at different predetermined speeds in opposite directions. 70
95. Mining apparatus including a frame supporting at one end thereof cutting mechanism, and means for effecting propulsion of 75 said frame during cutting in a path parallel to the major dimension of said frame including at the end of said frame remote from said cutting mechanism a driving member rotatable upon a horizontal axis extending longitudinally of said frame, and driving means for said cutting mechanism and said member including a motor disposed between said cutting mechanism and said member on said frame and having a power shaft parallel to the axis of rotation of said member, the driving means for said member including gearing for effecting drive thereof at different predetermined speeds in opposite directions. 80
96. In combination, a truck including a frame tiltable on a transverse pivot thereon, a longitudinally disposed mining machine on said frame including a cutter bar swingable by power in a plane about a pivot perpendicular thereto, and means for feeding the machine longitudinally and rotating the latter about a longitudinal axis and relative to said frame. 85
97. In a mining machine, a truck, a motor thereon having a casing rotatable about an axis coincident with the axis of motor rotation, cutting mechanism driven by said motor and carried by said casing, and truck driving mechanism including a plurality of friction clutches operatively connected to said motor. 90
98. In a mining machine, a truck, a motor thereon having a casing rotatable about an axis coincident with the axis of motor rotation, cutting mechanism driven by said motor and carried by said casing, truck driving mechanism including a plurality of friction clutches operatively connected to said motor, and casing rotating mechanism on said truck 100 operatively connectible to said truck driving mechanism. 105
99. In a mining machine, a wheeled support, a motor having a casing rotatably mounted for movement about its longitudinal axis on said support, cutting mechanism carried by said casing including a cutter bar, driving connections between said motor and the wheels of said support, and means for changing the angle of said casing relative to 110 support wheels to tilt said cutter bar. 115
100. In a mining machine, in combination, supporting means, a motor having a rotatable power shaft, a motor casing enclosing said motor and mounted on said supporting means for rotation about an axis coincident with the axis of said shaft, means driven by said motor for rotating said casing, a cutter carried by said casing, and means to angle said 120 casing relative to said supporting means. 125
101. In a mining machine, a motor having a casing rotatable about an axis coincident with the axis of motor rotation, cutting mechanism carried by said casing, and means 130

- for rotating said casing by said motor including a plurality of friction clutches.
102. In a mining machine, a driving motor having a housing rotatable about an axis coincident with the axis of motor rotation, cutting mechanism carried by said housing, and means for rotating said housing at a plurality of speeds including a plurality of selectively operable friction clutches. 5
103. In a mining machine, the combination of a truck supported body having a head overhanging one end of the truck and carrying a pivotally mounted cutter bar, a motor in said body, a reversible variable speed driving connection between the motor and the truck wheels permitting driving of the latter in opposite directions without reversal of the motor, and gearing driven by said motor for imparting angular movement to the cutter bar including separate friction clutches controlling opposite movements of the cutter bar. 10
104. In a mining machine, the combination of a truck supported body having a head overhanging one end of the truck and carrying a pivotally mounted cutter bar, a motor having a drive shaft extending in the direction of the longitudinal axis of said body, a reversible variable speed driving connection between one end of said shaft and the truck wheels permitting driving of the latter in opposite directions without reversal of the motor, gearing for imparting angular movement in opposite directions to said cutter bar, and a driving connection between the other end of said shaft and said gearing including frictional power transmitting elements. 15
105. In a mining machine, the combination of a truck supported body having a head overhanging one end of the truck and carrying a pivotally mounted cutter bar, a motor having a drive shaft extending in the direction of the longitudinal axis of said body, a reversible variable speed driving connection between one end of said shaft and the truck wheels permitting driving of the latter in opposite directions without reversal of the motor, gearing for imparting angular movement in opposite directions to said cutter bar, and a driving connection between the other end of said shaft and said gearing including separate variable friction clutches controlling the respective directions of angular movement of said bar. 20
106. In a mining machine, the combination of a truck supported body having a head overhanging one end of the truck and carrying a pivotally mounted cutter bar, a motor having a driving shaft extending in the direction of the longitudinal axis of said body, a reversible variable speed driving connection between one end of said shaft and the wheels and permitting driving of the latter in opposite directions without reversal of the motor and comprising gearing normally transmitting high and low speeds for opposite directions of travel of the truck respectively and including friction transmission for varying said speeds, gearing for imparting angular movement in opposite directions to said cutter bar, and driving connections between the other end of said shaft and said bar normally moving said bar at high and low speeds in its respective directions of movement including separate variable friction clutches 25
107. In a mining machine, a horizontal motor having a casing rotatable about an axis coincident with the axis of motor rotation, cutting mechanism carried by said casing, and means driven by said motor for rotating said casing at different speeds including a plurality of selectively operable speed controlling clutches. 30
108. In a mining machine, a horizontal driving motor, a casing housing said motor rotatable about the axis thereof, cutting mechanism carried by said casing, and means driven by said motor for rotating said casing at different speeds including an arcuate rack and gearing cooperating therewith, and a plurality of selectively operable speed controlling clutches controlling said gearing. 35
109. In a mining machine, a wheeled support, a driving motor having a casing rotatably mounted about the longitudinal axis thereof on said support, cutting mechanism including a cutter head rotatable with said casing, means driven by said motor for rotating said casing, and means for driving the wheels of said support. 40
110. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, a motor for driving said cutting mechanism, and means driven by said motor for raising and lowering said cutting mechanism into different parallel planes toward and from the axis of said second frame member. 45
111. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, and motor operated devices for raising and lowering said cutting mechanism into different parallel planes toward and from the axis of said second frame member. 50
112. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, and motor operated devices for raising and lowering said cutting mechanism into different parallel planes toward and from the axis of said second frame member. 55
113. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, and motor operated devices for raising and lowering said cutting mechanism into different parallel planes toward and from the axis of said second frame member. 60
114. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, and motor operated devices for raising and lowering said cutting mechanism into different parallel planes toward and from the axis of said second frame member. 65

lel planes toward and from the axis of said second frame member.

112. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, a motor for driving said cutting mechanism, motor operated devices for effecting bar swing at a cutting speed, and means driven by said motor for raising and lowering said cutting mechanism into different parallel planes toward and from the axis of said second frame member.

113. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain and motor operated devices for effecting bar swing at a cutting speed, and motor operated devices for raising and lowering said cutting mechanism into different parallel planes toward and from the axis of said second frame member.

114. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, cutting mechanism mounted on said support including a pivoted elongated plane cutter bar carrying an orbitally movable cutter chain, said cutting mechanism being movable vertically relative to said second frame member, a motor for driving said cutting mechanism, and means driven by said motor for raising and lowering said cutting mechanism into different parallel planes toward and from the axis of said second frame member.

115. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, cutting mechanism mounted on said support including a pivoted elongated plane cutter bar carrying an orbitally movable cutter chain, said cutting mechanism being movable vertically relative to said second frame member, and motor operated devices for raising and lowering said

cutting mechanism into different parallel planes toward and from the axis of said second frame member.

116. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, cutting mechanism mounted on said support including a pivoted elongated plane cutter bar carrying an orbitally movable cutter chain and motor operated devices for effecting bar swing at a cutting speed, said cutting mechanism being vertically movable relative to said second frame member, a motor for driving said cutting mechanism and means driven by said motor for raising and lowering said cutting mechanism into different parallel planes toward and from the axis of said second frame member.

117. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, cutting mechanism mounted on said support including a pivoted elongated plane cutter bar carrying an orbitally movable cutter chain and motor operated devices for effecting bar swing at a cutting speed, said cutting mechanism being vertically movable relative to said second frame member, and motor operated devices for raising and lowering said cutting mechanism into different parallel planes toward and from the axis of said second frame member.

118. In a mining machine, a wheel supported frame member pivoted to rock on a transverse axis, a second frame member pivotally connected to the first frame member to rock on a longitudinal axis, cutting mechanism mounted on said second frame member and having angular movement with respect thereto, said cutting mechanism including a pivoted elongated plane cutter bar carrying an orbitally movable cutter chain, a motor for driving said cutting mechanism means driven by said motor for raising and lowering said cutting mechanism into different parallel planes toward and from the axis of said second frame member, and motor driven mechanism operative to drive the wheels of the machine at a cutting speed.

119. In a mining machine, a wheel supported frame member pivoted to rock on a transverse axis, a second frame member pivotally connected to the first frame member to rock on a longitudinal axis, cutting mechanism mounted on said second frame member and having angular movement with respect

thereto, said cutting mechanism including a pivoted elongated plane cutter bar carrying an orbitally movable cutter chain and motor operated devices for effecting bar swing at a cutting speed, motor operated devices for raising and lowering said cutting mechanism into different parallel planes toward and from the axis of said second frame member, and motor driven mechanism operative to drive the wheels of the machine at a cutting speed.

120. In a mining machine, a wheel supported frame member pivoted to rock on a transverse axis, a second frame member pivotally connected to the first frame member at the front end thereof to rock on a longitudinal axis, a support mounted on said second frame member and having angular movement with respect thereto, cutting mechanism mounted on said support including a pivoted elongated plane cutter bar carrying an orbitally movable cutter chain and motor operated devices for effecting bar swing at a cutting speed, said cutting mechanism being adjustable vertically relative to said second frame member, motor operated devices for raising and lowering said cutting mechanism into different parallel planes toward and from the axis of said second frame member, and motor operated devices operative to drive the wheels of the machine at a cutting speed.

121. In a mining apparatus, a wheel mounted support adapted to run along a trackway, a motor on said support, cutting mechanism on said support and driven by said motor including a pivoted elongated plane cutter bar carrying an orbitally movable cutter chain, means driven by said motor for vertically rectilinearly adjusting said bar into different parallel horizontal planes relative to said support, and mechanism for tilting said support about a transverse axis to change the angle of said cutter bar relative to the horizontal.

122. In a mining apparatus, a wheel mounted support adapted to run along a trackway, a motor on said support, cutting mechanism on said support and driven by said motor including a pivoted elongated plane cutter bar carrying an orbitally movable cutter chain, motor operated devices for effecting bar swing at a cutting speed, and means driven by said motor for vertically rectilinearly adjusting said bar into different parallel horizontal planes relative to said support, and mechanism for tilting said support about a transverse horizontal axis to change the angle of said cutter bar relative to the horizontal.

123. In a mining apparatus, a wheel mounted support adapted to run along a trackway, a motor on said support, cutting mechanism on said support and driven by said motor including a pivoted elongated plane cutter bar carrying an orbitally mov-

able cutter chain, motor operated devices for vertically rectilinearly adjusting said cutter bar at a bar positioning speed into different parallel horizontal planes relative to said support, and mechanism for tilting said support about a transverse axis to change the angle of said cutter bar relative to the horizontal.

124. In a mining apparatus, a wheel mounted support adapted to run along a trackway, a motor on said support, cutting mechanism on said support and driven by said motor including a pivoted elongated plane cutter bar carrying an orbitally movable cutter chain, motor operated devices for effecting bar swing at a cutting speed, motor operated devices for vertically rectilinearly adjusting said cutter bar at a bar positioning speed into different parallel horizontal planes relative to said support, and mechanism for tilting said support about a transverse axis to change the angle of said cutter bar relative to the horizontal.

125. In a mining apparatus, a wheel mounted support adapted to run along a trackway, cutting mechanism on said support including a cutter carrying head rotatable on a longitudinal axis, an elongated plane cutter bar pivotally mounted on said head and carrying an orbitally movable cutter chain, a motor for driving said cutting mechanism, means driven by said motor for adjusting said bar into different parallel horizontal planes toward and from the axis of head rotation, and mechanism for tilting said cutting mechanism about a transverse axis to change the angle of said cutter bar relative to the horizontal.

126. In a mining apparatus, a wheel mounted support adapted to run along a trackway, cutting mechanism on said support including a cutter carrying head rotatable on a longitudinal axis, an elongated plane cutter bar pivotally mounted on said head, a motor for driving said cutting mechanism, motor operated devices for effecting bar swing at a cutting speed, means driven by said motor for adjusting said cutter bar into different parallel horizontal planes toward and from the axis of head rotation, and mechanism for tilting said cutting mechanism about a transverse axis to change the angle of said cutter bar relative to the horizontal.

127. In a mining apparatus, a wheel mounted support adapted to run along a trackway, cutting mechanism on said support including a cutter carrying head rotatable on a longitudinal axis, an elongated plane cutter bar pivotally mounted on said head, and motor operated devices for effecting bar swing at a cutting speed, motor operated devices for adjusting said bar into different parallel horizontal planes toward and from the axis of head rotation, and mechanism for tilting said cutting mechanism about a trans-

verse axis to change the angle of said cutter bar relative to the horizontal.

128. In a mining apparatus, a wheel mounted support adapted to run along a trackway, cutting mechanism on said support including a cutter carrying head rotatable on a longitudinal axis, an elongated plane cutter bar pivotally mounted on said head, and motor operated devices for effecting bar swing at a cutting speed, motor operated devices for effecting rotation of said head, motor operated devices for adjusting said bar into different parallel horizontal planes toward and from the axis of head rotation, and mechanism for tilting said cutting mechanism about a transverse axis to change the angle of said cutter bar relative to the horizontal.

129. In a mining apparatus, a wheel mounted support adapted to run along a trackway, a motor on said support, cutting mechanism on said support including a cutter carrying head rotatable on a longitudinal axis, an elongated plane cutter bar pivotally mounted on said head, mechanism driven by said motor for effecting bar swing at a cutting speed, mechanism driven by said motor for effecting head rotation, mechanism driven by said motor for adjusting said bar into different parallel horizontal planes toward and from the axis of head rotation, and mechanism for tilting said cutting mechanism about a transverse axis to change the angle of said cutter bar relative to the horizontal.

130. In a mining apparatus, a wheel mounted support adapted to run along a trackway, a motor on said support, cutting mechanism on said support including a cutter carrying head rotatable on a longitudinal axis, an elongated plane cutter bar pivotally mounted on said head, mechanism driven by said motor for effecting bar swing at a cutting speed, mechanism driven by said motor for effecting head rotation, mechanism driven by said motor for adjusting said bar into different parallel horizontal planes toward and from the axis of head rotation, mechanism for tilting said cutting mechanism about a transverse axis to change the angle of said cutter bar relative to the horizontal, and mechanism driven by said motor for driving the wheels of said support at a cutting speed.

131. In a mining apparatus, a wheeled support, a horizontal motor thereon having its casing rotatable about a longitudinal axis coincident with the axis of motor rotation, cutting mechanism carried by said rotatable motor casing, and mechanism driven by said motor for effecting rotation of said motor casing about its axis.

132. In a mining apparatus, a wheeled support, a horizontal motor thereon having its casing rotatable about a longitudinal axis coincident with the axis of motor rotation, cutting mechanism carried by said rotatable motor casing including an elongated plane

cutter bar mounted for swinging movement about an axis perpendicular to a line including the axis of rotation of said motor casing, and mechanism driven by said motor for effecting rotation of said motor casing about its axis.

133. In a mining apparatus, a wheel mounted support adapted to run along a trackway, cutting mechanism on said support including a pivoted plane cutter bar swingable in horizontal planes to cut horizontal kerfs and carrying an orbitally movable cutter chain, motor operated means for adjusting said bar rectilinearly into different parallel horizontal planes relative to said support at a bar positioning speed, and mechanism for tilting said support about a transverse axis to change the angle of said cutter bar relative to the horizontal.

134. In a mining apparatus, a wheel mounted support adapted to run along a trackway, cutting mechanism on said support including a pivoted elongated plane cutter bar swingable in horizontal planes to cut horizontal kerfs and carrying an orbitally movable cutter chain and motor operated devices for effecting bar swing at a cutting speed, motor operated devices for vertically rectilinearly adjusting said bar at a bar positioning speed into different parallel horizontal planes relative to said support, and mechanism for tilting said cutter bar about a transverse axis while the bar pivot is disposed in a vertical plane lying substantially midway between the sides of the apparatus, to change the angle of said cutter bar relative to the horizontal.

135. In a mining apparatus, a wheel mounted support adapted to run along a trackway, a motor carried by said support, a cutter support mounted on the forward end of said support and including a vertical guideway and a frame slidably mounted for vertical adjustment in said guideway, cutting mechanism on said slideable frame including a pivoted elongated plane cutter bar swingable in horizontal planes to cut horizontal kerfs and carrying an orbitally movable cutter chain, and mechanism driven by said motor for effecting bar swing at a cutting speed, mechanism driven by said motor for adjusting said cutter bar vertically along said guideway into different parallel horizontal planes relative to said support, and mechanism for tilting said support about a transverse axis to change the angle of said cutter bar relative to the horizontal.

136. In a mining apparatus, a portable support, a body mounted thereon, a motor carried by said body, cutting mechanism carried by said body and driven by said motor, and means for adjustably supporting said body on said support for rotation about a horizontal longitudinal axis coincident with the axis of said motor including arcuate

guiding means carried by and arranged externally of said body, and cooperating guiding means carried by said support.

137. In a mining apparatus, a portable support, a body mounted thereon, a motor carried by said body, cutting mechanism carried by said body and driven by said motor, means for adjustably supporting said body on said support for rotation about a horizontal longitudinal axis including arcuate guiding means carried by said body, cooperating guiding means carried by and partially surrounding said support, and mechanism driven by said motor for effecting rotation of said body relative to said support.

138. In a mining apparatus, a wheeled truck, a mining machine rotatably mounted thereon including a body, a motor carried by said body having a power shaft, and cutting mechanism carried by said body and driven by said motor, said cutting mechanism including a plane cutter disposed in a plane parallel to the axis of rotation of said motor power shaft, and means for adjustably supporting said machine on said truck for rotation about a horizontal longitudinal axis coincident with the axis of said motor power shaft including bearing means for said machine disposed wholly outside of the lateral limits of said body.

139. In a mining apparatus, a portable support, a body mounted thereon, a motor carried by said body and having a power shaft, cutting mechanism carried by said body and driven by said motor, said cutting mechanism including a plane cutter disposed in a plane parallel to the axis of rotation of said motor power shaft, and means for adjustably supporting said body on said support for rotation about a horizontal longitudinal axis coincident with the axis of said motor power shaft comprising cooperating arcuate guiding means carried by said body and support including a guiding element partially surrounding said body.

45 In testimony whereof I affix my signature.
MORRIS P. HOLMES.
